9 Claims. (Cl. 233—1)

1

The present invention relates to new and useful improvements in centrifuge connections.

One object of the invention comprises among others an improved and simplified construction for connecting feed and discharge conduits to centrifuges. This and further objects of the invention may be seen from the following description.

In known centrifuge constructions, the conduits which feed, discharge and convey the liquids from one centrifugal stage into the next one, or which connect to control agents, are either arranged concentrically (i. e. within one another) or side by side. The latter arrangement is in many cases preferable and the conduits are preferably provided in a stationary shaft extending above the centrifuge.

According to the invention an easily detachable connection of feed and discharge lines and of control devices to said shaft is obtained by the provision of a manifold collar pressed or secured to the end of the shaft portion extending beyond the centrifugal drum. This collar may be secured and pressed to the end of the shaft by means of a flange. Alternatively it may consist of two parts embracing the end of the shaft. The latter is preferably provided with substantially parallel, substantially flat surfaces and bores, preferably counter-sunk and connecting these surfaces with the longitudinal shaft conduits. The parts of the manifold collar are pressed against the parallel surfaces and the duct to duct areas are sealed by means of packings and preferably resiliently compressed gaskets or the like, preferably arranged in grooves provided on either the inner collar or outer shaft surface. Clearances and sealing are preferably such that the collar can be easily removed after the pressure bolts have been loosened or taken off.

An embodiment of the invention is shown by way of example in the accompanying drawings in which:

Fig. 1 is a vertical cross-section, partly diagrammatic, of an extraction type centrifuge;

Fig. 2 is a cross-sectional view of part of the construction shown in Fig. 1 at right angles thereto;

Fig. 3 is a cross-sectional top view of the end of the centrifuge shaft in the plane III—III of Fig. 2;

Fig. 4 is a cross-sectional top view of the construction shown in Fig. 2 in the plane IV—IV thereof; and

Fig. 5 is a cross-sectional top view of the end 55 of the conduit 8 of the shaft 1.

2

of the centrifuge shaft in the plane V—V of the construction of Fig. 2.

The shaft 1 extending beyond the centrifuge drum is provided with parallel channels or conduits through which the liquids are passed. The liquid to be treated is supplied to the centrifuge drum through the channel 2 and the extracting agent or solvent is fed to the drum through the channel 3. The channel 4 serves for discharging the liquid to be treated and the channel 5 for conveying the extracting agent out of the drum.

A manifold collar 10 is provided for connecting all external feed and discharge lines and the control devices with the conduits lying within the shaft, the collar being mounted on or embracing the shaft 1. A manometer 6 serves to check the feed pressure of the stripping disc 9. The manometer 6 is connected with the space 7 by way of conduit 8 of the shaft and its base is movably secured in collar 10. The manometer base is removably pressed with its packing 12 against shaft 1 by means of differentially threaded tubular member 11. Feed and discharge lines may be connected to or within the collar ducts 13, 14, 15 and 16 in a similar manner. The ends of the feed and discharge lines may be thus pressed in the same manner against the shaft by means of differentially threaded tubular members suitably fitted with packings.

Collar 10 consists preferably of two parts as may be seen from Figs. 2 and 4. The packings pressed against shaft 1 are indicated as 17, 18, 19, and 20.

As illustrated in Fig. 3 the end of the shaft is provided with opposing parallel surfaces which have counterbores 21 and 22 respectively. The counterbore 21 extends to conduit 3 of the shaft and counterbore 22 to conduit 5. At the level 40 of the upper connections 13, 15 of the collar, conduits 25 and 26 (Fig. 4) extend within the shaft from the parallel surfaces 23, 24 to the longitudinal conduits 2 and 4. The sections of collar 10 are forced together by means of bolts 27 and 28 pressing the various packings on gaskets against the shaft 1. The collar may be removed from shaft 1 after the bolts 27, 28 have been loosened or removed and after the differentially threaded tubes, as exemplified by tube 11, have been backed off. At the level of the manometer-connection the shaft 1 is preferably also provided with another packing surface 30 (Fig. 5) for the manometer base 12. A bore 29 extends from the preferably flat surface 30 to the conduit 8 of the shaft 1.

As will be thus seen from the foregoing, the invention essentially comprises in a centrifuge having a stationary external central shaft portion and longitudinal conduit passages therein, the improvement of means defining on said shaft portion at least one substantially flat surface, means defining at least one first duct from said surface to at least one of said passages, a removable manifold member around said shaft portion having an inner surface substantially in alignment with said outer shaft surface, means defining a second duct leading from outside said collar to said inner surface in substantial registry with said first duct, means for substantially sealing the duct-to-duct area against liquid leakage, means on said second duct for removably securing a conduit in liquid-tight connection therewith, and means for pressing said collar member in gasket tight surface-to-surface relation with said shaft.

We claim:

1. In a centrifuge having an extraction stationary external central shaft portion provided with longitudinal conduit passages, the improvement comprising means defining on said shaft portion opposing outer substantially flat parallel surfaces, means defining first ducts from said surfaces to said passages, and a removable manifold collar around said shaft portion having two opposing inner surfaces substantially fitting said outer shaft surfaces, means defining second ducts leading from outside said collar to said inner surfaces, one for and in substantial registry with each of said first ducts, means for substantially sealing each duct-to-duct area against liquid leakage, and means on said second ducts for removably securing conduits in liquid-tight connection therewith.

2. Improvement according to claim 1 in which said shaft portion has additionally a sealing surface and crossbore extending therefrom to one of said longitudinal passages, in which said collar defines an aperture, in which a pressure gauge is provided extending with its base through said aperture and in which said base is pressed against said sealing surface with a duct-to-duct area sealing gasket secured between said base and said sealing surface.

3. Improvement according to claim 2 in which said base is held in said collar in gasket sealing contact with said sealing surface by a differentially threaded tubular member within said aperture around said base.

4. Improvement according to claim 1 in which said means for removably securing conduits are threaded areas within said second conduits for receiving a differentially threaded tubular securing member.

5. Improvement according to claim 1 in which said sealing means are resilient gasket means carried in grooves in at least one of said inner and said outer surfaces.

6. Improvement according to claim 5 in which said means for removably securing conduits are threaded areas within said second conduits for receiving a differentially threaded tubular securing member.

7. Improvement according to claim 6 in which said shaft portion has additionally a sealing surface and crossbore extending therefrom to one of said longitudinal passages, in which said collar defines an aperture, in which a pressure gauge is provided extending with its base through said aperture and in which said base is pressed against said sealing surface with a duct-to-duct area sealing gasket secured between said base and said sealing surface.

8. Improvement according to claim 7 in which said base is held in said collar in gasket sealing contact with said sealing surface by a differentially threaded tubular member within said aperture around said base.

9. In a centrifuge having an extraction stationary external central shaft portion provided with longitudinal conduit passages, the improvement comprising means defining on said shaft portion at least one substantially flat surface, means defining at least one first duct from said surface to at least one of said passages, a removable manifold member around said shaft portion having an inner surface substantially in alignment with said outer shaft surface, means defining a second duct leading from outside said collar to said inner surface in substantial registry with said first duct, means for substantially sealing the duct-to-duct area against liquid leakage, means on said second duct for removably securing a conduit in liquid-tight connection therewith, and means for pressing said collar member in gasket tight surface-to-surface relation with said shaft.
